UNITED STATES PATENT OFFICE.

CHARLES BURKELMAN, OF NEW YORK, N. Y.

DRAIN PROTECTOR.

Application filed August 6, 1927. Serial No. 211,220.

This invention relates to drain protectors. The primary object of the invention is to provide a protector which may be placed over the outlet drain of a roof or other drain and which will prevent the stopping up of the drain through the accumulation of leaves, sticks or trash of any sort.

A further object is to provide a device of this character which permits water which may accumulate on the roof to escape at different levels so that if the device is partially stopped up and the level of water rises it will still escape through the device.

A further object is to provide a device of this character which can be manufactured and sold at a reasonably low price, which will be self-sustaining in its position over a drain outlet and which will be strong and durable in use.

With these and other objects in view, the invention consists in certain novel features of construction and combinations and arrangements of parts, which will be more fully hereinafter described and pointed out in the claims.

In the accompanying drawings—

Figure 1 is a perspective view showing my improved device in operative position on a roof;

Figure 2 is a view in longitudinal section through the device and through a portion of the roof and outlet drain;

Figure 3 is a view in section on the line 3—3 of Figure 2.

1 represents a roof and 2 a wall around the roof. 3 is an outlet drain in the roof having a removable screen 4 in its upper end although of course the invention is not limited to the employment of such a screen.

5 represents my improved protector, which is hollow and of general triangular form in transverse section having closed ends 6, 6 and having a series of slots 7 in the converging side walls of the device.

On opposite ends of the device water inlets 8 and 9 are fixed or made integral and communicate with the interior of the device. These inlets 8 and 9 are in different horizontal planes. In other words, one is in a plane higher than the other and each of these inlets are in the shape of T-couplings horizontally positioned and open at their upper and lower ends, as clearly indicated in Figure 2.

When the device is in operative position,

as shown in Figure 2, the water will drain from the roof through the slots 7 and down the drain under ordinary conditions, but should these slots 7 become clogged, due to trash, ice or any other cause, the water would still enter the device and pass down through the drain through one or the other of the inlets 8 and 9.

I have shown in Figure 2, four water levels, indicated by dotted lines 10, 11, 12 and 13. Should the slots 7 be stopped up when the water reaches the level 10 it will flow through the inlet 8 into the device and down the drain. Should the lower end of this inlet 8 be stopped up, the level of water would rise to the line indicated by the reference numeral 13 and would flow through the inlet 9. Should this lower end of the inlet 9 be stopped up, the water will rise to the level of the line 11 and flow down through the inlet 8, and if this becomes stopped up the water level may rise to the point indicated by the line 12 and flow down through the inlet 9.

It will thus be noted that with my improved device an inlet for water is had to the drain until the device is entirely covered by trash or other materials, and as it is difficult to believe that the occasion will ever arise where all of the inlets to the device and drain are stopped there will be a practical assurance of drainage from the roof regardless of conditions.

It is a well known fact that a great amount of damage is caused by the stoppage of roof outlet drains and the accumulation of water on the roof but with my improved device in position over the drain a complete stoppage of the escape of water is practically impossible, and liability of damage due to accumulation of water on the roof is nullified.

The inverted inlet to the strainer prevents material floating on the surface from entering the device as no water can flow until the water level generally rises to the height of the horizontal inlet. The heavier material cannot be drawn into the device.

Various changes and alterations might be made in the general form of the parts described without departing from the spirit of the invention and hence I do not limit myself to the precise details set forth but consider myself at liberty to make such changes and alterations as fairly fall within the spirit and scope of the appended claims.

I claim:

1. A drain protector, comprising a hollow body, adapted to be positioned over a drain and having openings therein, and an inlet at one end of the body of general T-shape communicating with the interior of the body and admitting water to the body from different levels.
2. A drain protector, comprising a hollow body adapted to be positioned over a drain and having openings therein, an inlet at one end of the body of general T-shape communicating with the interior of the body and admitting water to the body from different levels, and a second inlet similar to the first mentioned inlet at the other end of the body and located in a higher plane than the first mentioned inlet.
3. A drain protector, including an open body adapted to be positioned over a drain and having slots in its side walls and T-shaped inlets at its ends. 20
4. A drain protector, including an open body adapted to be positioned over a drain and having slots in its side walls and T-shaped inlets at its ends, said inlets being located in different planes. 25
5. A device of the character described, including a hollow body of general triangular shape in vertical transverse section having slots in the inclined walls thereof and having inlets in the ends thereof. 30

Signed at New York, in the county of New York and State of New York this 4th day of August, A. D. 1927.

CHARLES BURKELMAN.
